SAFETY SWITCH LOCK FOR RAILROADS

Lucian A. Smith, Glenburnie, Md.

Application October 2, 1944, Serial No. 556,836

4 Claims. (Cl. 246—393)

1

This invention refers to railroad track mechanism and more particularly to switch devices for same. It has among its objects to provide a switch that will be easier to repair when damaged by trains travelling in the wrong direction throwing the moveable switch points into another track position from the one it had first. Another object is to have a signal attached to the switch mechanism so arranged that it will indicate the true situation with regard to the position of the switch whether damaged or not. Still another object is to provide arrangements for operatively locking the parts of the switch together in the position given by the train under the conditions stated. A further object is to have the lever and weight mechanism used for conventionally operating the rails at the switch rendered independent of the device yet working the signal through the device to show the proper indication, and true position of the switch. A still further object is to have the mechanism of the device designed to automatically adjust itself after its shearing safeguard has been used.

Other objects will become apparent as the invention is more fully set forth.

In the conventional type of switch used on railroads, the operation of the switch points are controlled by a weight and lever mechanism attached to a switch stand, which also controls the position of the signal light to which it is attached. The operation of a train running against the rear of the switch in locked position operates the mechanism so it shears or breaks off a lug or dog on one of its parts in the switch stand which renders it inoperative and allows the switch points to float loosely back and forth, in a direction opposite to the position shown by the signal lights thereby causing train wrecks until an operator arrives and takes the switch stand down and repairs it by putting its spare lug into commission. In this device the operation of its mechanism in the wrong direction changes the signal light to show the new position of the switch points and causes shearing of replaceable bolts or shearing pins which are readily accessible for replacing from the outside without dismantling the switch stand and without breaking the lug or dog in the switch stand. When the replaceable bolts are sheared off in this device a plunger securely locks the switch point in its new position as shown by the signal light after which it cannot be operated by the regular lever mechanism and weight. To repair this device the operator raises the plunger, moves the lever arm and drops the new shearing bolts or

2

pins into position without touching the switch stand.

In conjunction with the description herein appended, drawings are provided indicating a structure of a switching device embodying this invention as illustrated, in which:

Figure 1 is a plan view of the switching and signalling device embodying this invention;

Figure 2 is a sectional view of Figure 1, taken along line 2—2;

Figure 3 is a plan view of the shearing and self-locking member shown in Figure 1;

Figure 4 is a sectional view taken along line 4—4 of Figure 3;

Figure 5 is a sectional view taken along line 5—5 of Figure 3;

Figure 6 is a sectional view of Figure 3 taken along line 4—4 showing the pin sheared and the top and bottom plates moved until the choke bolt has dropped into position and locked the upper and lower plates together, and

Figure 7 is a sectional view taken along line 7—7 of Figure 6.

Similar reference characters refer to similar parts throughout the drawings.

Referring to the parts shown in the drawings 1, 2, 3 and 44 respectively indicate the main track rails and the side track rails of a switch, in which 2 and 3 are those which are moveable by the switch. The moveable rails 2 and 3 are rigidly carried on an underplate 4 which is operated from the signal side of the tracks by a weighted lever mechanism 5 connected to it through a link 6, and top plate 7. The top plate 7 slides on the underplate 4 and has a longitudinal bevelled slot 8 with end portions 15 and 20 enlarged circularly for purposes to be explained. A pair of bolt holes 9 are located on the rail-side end portion 10 of the top plate 7 and are aligned with corresponding holes 11 in the underplate 4. These holes serve to take shear pins 12 that are sheared off when the underplate 4 is train operated against the stationary switch and locked weighted lever. These pins are preferably locked in place with cotter pins or otherwise. The top plate 7 is moveable with the under plate under normal conditions, being connected thereto by the shear pins 12 and is guided by a choke bolt 13 in its travel back and forth to throw the moveable rails in the conventional way. This choke bolt is smaller at its two middle portions 17 so that portion can ride in the slot 8 under normal conditions. The upper portion of the choke bolt is larger and prevents it from passing down through the slot 8 until the pins 12 are sheared off and allow the underplate to move

until the large end portions or terminals 15 or 20 are reached, and align with the hole 45. The choke bolt through the action of springs 16 which press down on the cross bar 18 lock the top and under plate together until new shear bolts are inserted.

The bar 18 is guided vertically on the posts 19 on which the springs are mounted. The under plate 4 supports the posts. Suitable cross-ties 21 are used ordinarily to hold the switch unit and the various elements of this structure in position, adjacent the tracks or rails operated by it. When the choke bolt is set in hole 20 to the right in the drawing, the track to the left is open and the train coming in the direction of the arrow shown in Figure 1 will take the through track to the left.

When in the opposite hole 15 the train will take the side track to the right. The link 6 is hingedly attached to the top plate 7 and switch mechanism 5. The signal 22 and lamp 23 are operated by the under plate 4 with it. The signal and lamp are mounted on a vertical rod 24 which is loosely connected to a slotted tubular post 25. The connection between the lamp and signal and the under plate 4 consists of an offset piece 26 and rod 46 held together as indicated. The post is supported on a base 27. Independently connected to the top plate 7 is a switch-moving mechanism 5 having a lever 29 and weight 30 of conventional form. This mechanism operates the moveable rails at the switch unit normally through links and gearing as shown without passing through the signal and light. The movement of the proper rails however would tend to "throw" the weight and lever to its opposite position but cannot, so the shear pins break. This would be the case when a train comes through the switch from one of the branch tracks when the switch is set for the other track. When the train comes from one of the tracks in reverse, and the switch is open to the other track, the wheels of the train will force the moveable rails of the first mentioned track, at the switch, over to the open position for the track the train is travelling from. In Figure 1, this would be the track leading from curved rails 3 and 44 and would force over the rails 2 and 3 towards the left side or straight track 1 of the figure. Since the signal and light indicate the position of the tracks in the first placement looking in direction of arrow, the movement of the rails 2 and 3 will force the under plate 4 to the left also and through it and offset piece 26 and rod 46 will turn the signal and light through one quarter of a revolution and indicate the other signal, which will be red, looking in direction of arrow, because the train ran through the rear on the red signal. At the same time the resistance offered by the weighted lever mechanism 5 will cause the shear pins to shear off.

Summing the operation up, the setting of the rails by the switch unit opens up the track selected from the two branches. In Figure 1 the track to the left is open. A train coming down this track in reverse will not operate the signal or weighted lever mechanism, because the switch has left same open. If the train came down the track to the right in reverse, it would have to force the rails 2 and 3 over to permit it to pass through properly. When this occurs, the under plate 4 moves to the left with these rails and tries to operate the weight-lever mechanism 5, which resists, and causes the stress on the shear pins 12 and breaks them. The underplate is then free from the top plate and continues to the left carrying the choke bolt 13 and cross-plate, or bar 18

with it through the operation of the posts 19 against them. The top plate 7 cannot move so the choke bolt 13 travels through its slot 8 until it reaches the large hole 15 or 20 at the terminus of same. The choke bolt actuated through the pressure of the springs 16 passes down into the holes 15 and 45 locks the top plate 7 and under-plate 4 solidly together. The weighted lever mechanism cannot operate it, because its position is opposite to its proper movement to throw the switch back to its original position. While the cross-plate or bar 18 was being moved, it rode against the V-cam members 31 or riding plates 31 and was lifted over same and dropped on the other side and became caught, so there would be no tendency of the switch points to get displaced and cause wrecks. This V-cam member consists of a strap of metal bent into V-form inverted with arms drilled for bolts 32 to fasten same to one of the ties 21 and in the line of travel of the cross-plate 18. When the choke bolt is locked as stated above, the unit is in condition to be repaired but will hold switch in operating position. While the underplate is travelling under the action of the rails and train and is moving the posts, cross-plate and choke bolt, its connections to the signal and lamp through the parts, 24 and 25, 26 and 46 cause it to turn same to the position consistent with its new position after the passage of the train in reverse. When the signal shows this position, it warns the operators to repair and reset it. The movement of the rails 2 and 3 when the other track is open, by a train, to the right produces a similar movement of the parts only in the opposite direction. The underplate 4 is slidably attached to track rails 1 and 44, by bolts 50 operating in slots 51.

While but one general form of the invention is shown in the drawings and described in the specifications, it is not desired to limit this application for patent to the particular form or in any other way otherwise than limited by the scope thereof, as it is appreciated that other forms of construction could be made that would use the same principles and come within the scope of the appended claims.

Having thus described the invention, what is claimed is:

1. A railroad switch unit of the class described comprising in combination an underplate arranged for attachment to the moving switch points of a railroad switch and for travelling therewith, a top plate mounted over the underplate, said top plate having a longitudinal slot therein and its termini enlarged at both ends, a choke bolt having its shank in plural sizes so it can ride in the longitudinal slot with the portion of one size therein and move into and project through the termini when the portion of another size is aligned therewith, means for normally holding the choke bolt in a relatively stationary position over the top plate, shear bolts for holding the underplate to the top plate for normal operation and to be sheared to loosen said plates from one another when in abnormal operation, the movement of the underplate after shearing of said shear bolts continuing and carrying the choke bolt therewith through the slot until a terminus is reached so it can lock therein with the switch points in the abnormal position derived from said abnormal movement, and hold the top plate rigidly thereto so it will operate sequentially by the underplate directly, a signal device connected with the bottom plate adapted to change the indication thereof during

the stroke of the bottom plate in coordination with the position of the points.

2. A railroad switch unit of the class described comprising in combination an underplate arranged for attachment to the moving switch points of a railroad switch and for travelling therewith, a top plate mounted over the underplate, said top plate having a longitudinal slot therein and its termini enlarged at both ends, a choke bolt having its shank in plural sizes so it can ride in the longitudinal slot with the portion of one size therein and move into and project through the termini when the portion of another size is aligned therewith, means for normally holding the choke bolt in a relatively stationary position over the top plate, shear bolts for holding the underplate to the top plate for normal operation and to be sheared to loosen said plates from one another when in abnormal operation, the movement of the underplate after shearing of said shear bolts continuing and carrying the choke bolt therewith through the slot until a terminus is reached so it can lock therein with the switch points in the abnormal position derived from said abnormal movement, and hold the top plate rigidly thereto so it will operate sequentially by the underplate directly, a signal device connected with the bottom plate adapted to change the indication thereof during the stroke of the bottom plate in coordination with the position of the points, and a riding plate arranged for the placement near the top plate for locking the choke bolt at the end of the stroke and permanently setting the points in the position derived from the abnormal movement, and the resulting shearing of said bolt.

3. A railroad switch unit of the class described comprising in combination an underplate arranged for attachment to the moving switch points of a railroad switch and for travelling therewith, a top plate mounted over the underplate, said top plate having a longitudinal slot therein and its termini enlarged at both ends, a choke bolt having its shank in plural sizes so it can ride in the longitudinal slot with the portion of one size therein and move into and project through the termini when the portion of another size is aligned therewith, means for normally holding the choke bolt in a relatively stationary position over the top plate, shear bolts for holding the underplate to the top plate for normal operation and to be sheared to loosen said plates from one another when in abnormal operation, the movement of the underplate after shearing of said shear bolts continuing and carry-

ing the choke bolt therewith through the slot until a terminus is reached so it can lock therein with the switch points in the abnormal position derived from said abnormal movement, and hold the top plate rigidly thereto so it will operate sequentially by the underplate directly, a signal device connected with the bottom plate adapted to change the indication thereof during the stroke of the bottom plate in coordination with the position of the points, and a riding plate arranged for the placement near the top plate for locking the choke bolt at the end of the stroke and permanently setting the points in the position derived from the abnormal movement, and the resulting shearing of said bolts, and a plurality of post members connected with the underplate, a crossplate carried by the said members and carrying the choke bolt for controlling the movement thereof in the slot, and means for operating the said plates for normal operation in conjunction with signal device.

4. A railroad switch unit for operating movable rail points connecting plural tracks together for guiding train wheels trailing thereon to one of said tracks selectively comprising in combination; a reciprocating underplate connected to the movable rails for moving same from guidable registry with one of said tracks to another, an overplate, shear pin means for rigidly attaching said overplate to said underplate including a socket therein, a choke pin mounted on said overplate and held in that position by said underplate while the shear pin means is normally positioned in the underplate and overplate, said choke pin being subject to lock in said underplate when an abnormal movement of the points registered as aforesaid, breaks the shear pin and allows the underplate to move in relation to the overplate and permit the choke pin to move into said socket and stay therein in permanent connection therewith to hold the rail points inoperatively in the position derived from said abnormal movement, and mechanism for operating the switch unit when in normal setting.
